in great demand in foreign countries.
T. A. Delano.
Life Preserver.

N° 22,021.

Patented Nov. 9. 1858.

UNITED STATES PATENT OFFICE.

T. A. DELANO, OF NEW YORK, N. Y.

IMPROVED LIFE-PRESERVING VESTS.

Specification forming part of Letters Patent No. 22,021, dated November 9, 1858.

To all whom it may concern:

Be it known that I, THOMAS A. DELANO, of the city, county, and State of New York, have invented a new and useful Improvement in Life-Preserving Vests for the Prevention of Drowning; and I do hereby declare that the following is a full, clear, and exact description of the same, reference being had to the accompanying drawings, forming part of this specification, in which—

Figure 1 is a view of a vest constructed according to my invention spread open. Fig. 2 is a view exhibiting the same in the condition in which it is worn as an ordinary vest. Fig. 3 is a view exhibiting the same in the condition in which it is worn when there is any risk of the wearer being precipitated into the water. Fig. 4 exhibits the air-inflated float of the vest spread out.

Similar letters of reference indicate corresponding parts in the several figures.

This invention relates to vests that are suitable for ordinary wear, but furnished between the exterior and the lining with a float of india-rubber or other flexible material that can be inflated at pleasure in a few moments without the removal of the vest from the person.

The drawings represent the application of the invention to a man's vest only; but by the term "vest" as employed in this specification I mean to include all close-fitting garments of similar character—*i. e.*, fitting to the upper part of the body and fastening in front—whether worn by men or women. The vest may be of any fashion to suit the taste.

A is the inflatable float, whose form is shown in Fig. 4, and the manner of applying it within the vest between the exterior and lining thereof is shown in Fig. 1 in dotted outline. This float is made with a cap a, which can be tucked into the vest or drawn out to a suitable position for the wearer to apply the mouth to its screw-valve mouth-piece b to inflate the float.

c c are the buttons, and d d the button-holes, of the vest, both arranged in the usual manner and used to fasten the vest when it is worn with the float A uninflated, as shown in Fig. 2.

e e are the elastic straps which constitute my invention, attached to the button-hole side of the vest at the back of the button-

holes, one opposite each button-hole, or every one but the bottom one, and gradually increasing in length from the bottom one upward. These straps are furnished with button-holes g g, which, when the button-holes d d are unfastened can be secured to the buttons c c, and they enlarge the vest sufficiently to permit the inflation of the float, and when the float is inflated they confine the vest snugly around the body; but at the same time by their elasticity prevent any painful pressure of the inner side of the inflated float (which by inflation assumes a rounded form) upon the chest of the wearer as the latter is expanded by the dilation of the lungs.

The straps e e may be buttoned to the buttons c c at all times, and the button-holes d d buttoned over them when the vest is worn on ordinary occasions, the middle portions of the straps being in that case tucked inside the vest out of sight, and all that would be necessary to prepare the vest for inflation would be to unbutton the button-holes d d. It is more convenient, however, to have a set of buttons f f inside the vest to which to button the holes g g of the straps by turning the straps back within the vest, as shown in Fig. 2, when the button-holes d d are used. In the latter method of arranging the straps when it is necessary to inflate the float after unbuttoning the holes d d, the holes g g will require to be unbuttoned from the buttons f f and buttoned onto c c.

It will be observed that the float A extends from the sides or breasts of the vest, across the back, and under the armholes. Thus an air-chamber extends almost entirely around the person of the wearer at that point where it will give the greatest support to the upper part of the body.

Having thus described my improvement, I claim and desire to secure by Letters Patent, as a new article of manufacture—

A life-preserved having elastic fastenings or straps e e and an inflatable air-chamber or float A extending from the breasts underneath the armholes, as herein shown and described.

T. A. DELANO.
